UNITED STATES PATENT OFFICE.

MARY J. CUNNINGHAM, OF BOSTON, MASSACHUSETTS.

BED-PAN.

SPECIFICATION forming part of Letters Patent No. 445,011, dated January 20, 1891.

Application filed May 29, 1890. Serial No. 353,653. (No model.)

To all whom it may concern:

Be it known that I, MARY J. CUNNINGHAM, a subject of the Queen of Great Britain, but at present residing at Boston, county of Suffolk, State of Massachusetts, have invented 5 an Improvement in Bed-Pan Cushions, of which the following description, in connection with the accompanying drawings, is a specification, like letters on the drawings representing like parts.

This invention has for its object the production of a novel cushion for the usual porcelain bed-pan, whereby the latter is made more comfortable and useful for the patient.

15 The cushion made in accordance with my invention is composed of a foundation to underlie the pan and a double-walled pad at one end thereof to cover the wedge shaped nose of the bed-pan up to the usual opening therein.

20 This pocket forms a bag for the reception of a fluid, such as air or water, either hot or cold, as considered best for the patient. The foundation-layer is large enough to extend under the bed-pan and backwardly beyond

25 the opening in the top of the pan, to thereby form a protection for the bedclothing. Preferably the foundation will be longer than the pan.

Figure 1 is a top or plan view of a bed-pan 30 with my improved cushion thereon in place; and Fig. 2, a section of the same in the dotted line α , Fig. 1, the bed-pan being shown in elevation.

The bed-pan A, of usual shape and material, has a beveled nose A', an opening A², 35 and a spout A³.

My improved cushion consists of a foundation-layer B of sufficient size to receive the pan well upon it, and the foundation will be 40 large enough to prevent the bottom of the pan from resting on the sheets on the bed, to

thereby fully protect the same. From at or about the points b I have connected to the foundation a pad or pocket C, composed of the double walls c c', so joined together as to 45 leave a space c², which may be filled through the tube c³ with a fluid, such as air or hot or cold water, as may be desired. The tube c³ has a suitable screw or other stopper c⁴.

The pad is of such length as to cover the 50 wedge-shaped upper side of the nose of the pan to or nearly to the edge 2 of the opening A², the cushion, constructed as described, being crowded closer and closer to the pan by the act of pushing the pan under the patient. 55

The extenstion of the pad entirely about the opening A² would make it harder to insert the pan under the patient; but by stopping the pad at or about the point described it acts as a cushion for the wedge-shaped nose 60 up to the point 2, leaving the walls of the opening free to contact directly with the patient, which tends to cleanliness and lessens the liability of accident to bedding.

I claim—

The herein-described bed-pan cushion, consisting of a double-walled pad and a foundation-layer B, the said pad being large enough to cover the wedge-shaped nose of the pan and form a yielding cushion over the said 70 nose, the foundation extending backwardly beyond the opening in the top of the pan to support the lower side of the pan, as and for the purpose set forth.

In testimony whereof I have signed my 75 name to this specification in the presence of two subscribing witnesses.

MARY J. CUNNINGHAM.
